CLAIM

I claim the ornamental design for a foot shaped yoga mat, as shown and described.

DESCRIPTION

FIG. 1 is a top isometric view of a foot shaped yoga mat showing my new design;

FIG. 2 is a right side elevation view thereof;

FIG. 3 is a left side elevation view thereof;

FIG. 4 is a front elevation view thereof;

FIG. 5 is a back elevation view thereof; and

FIG. 6 is a top plan view thereof; and,

FIG. 7 is a bottom side view thereof.
